UNITED STATES PATENT OFFICE.

AXEL JOHNSON, OF OAKLAND, CALIFORNIA, ASSIGNOR TO AMERICAN CAN COMPANY,
A CORPORATION OF NEW JERSEY.

CAN-HEAD-FEED MECHANISM.

1,074,325.

Specification of Letters Patent. Patented Sept. 30, 1913.

Application filed December 5, 1910. Serial No. 595,610.

To all whom it may concern:

Be it known that I, AXEL JOHNSON, a citizen of the United States, residing at Oakland, in the county of Alameda and State of California, have invented certain new and useful Improvements in Can-Head-Feed Mechanism, of which the following is a specification.

The invention relates to a simple, efficient and durably constructed feeder for automatically delivering can heads or covers to can bodies as conveyed from a can body end flanger to the can head double seaming mechanism, the invention being designed for use in connection with can making factories for positioning a can head or cover relative to an end flanged can body as conveyed toward the seaming mechanism for securing the can head or cover to the flanged end of the can body and in canning establishments or factories for feeding the can heads or covers to the flanged end of a filled can as conveyed toward the seaming mechanism for securing the head or cover to the flanged end of the can.

The hereinafter described can head or cover feeder comprises a can head holder and a can head feed slide or blade adapted to automatically feed or deliver the can heads or covers from the holder one by one to the flanged can bodies as they are moved toward the can head feed mechanism, the releasing means for the held can heads or covers being actuated by the action of the propelled end flanged cans or can bodies and means for forcing inwardly the feed blade to cut out or separate the lowermost can head from the stack of held heads and holding such separated body of can heads within the can head holder.

To comprehend the invention reference should be had to the accompanying sheet of drawings, wherein—

Figure 1 is a side sectional view of the improved can head feeder, the means for feeding the flanged can bodies thereto and actuating the lever for forcing inwardly the can head feed slide blade being partly broken away and in vertical section. Fig. 2 is a part broken plan view of the mechanism disclosed by Fig. 1 of the drawings. Fig. 3 is a detail broken plan view of the rotary carrier for conveying the flanged cans or bodies toward the can head cover or feed mechanism. Fig. 4 is a plan view of the can

head feed blade and the can head holder. Fig. 5 is a broken detail elevation, partly in section, of the can head or cover holder and the feed blade in position for sustaining the body of can heads or covers. Fig. 6 is a broken detail elevation of the can carrier and can head guide ring, the latter being sectioned.

In the drawings, the numeral 1 is used to represent the frame of the machine, the same being of any suitable form or construction adapted to give support to the other parts, and 2 a rotary carrier provided with external segmental can holders 3. This carrier 2 is mounted on a vertical shaft 4 extended through the frame of the machine, to the lower end of which is secured a drive gear 5 driven from any suitably connected drive mechanism.

To a bracket 6 upwardly extended from the frame 1 is secured a guide plate 7, through which works a reciprocating feed blade 8, which moves beneath a guide ring 9 attached to the inner end of the guide plate 7 to stand in vertical alinement with one of the external segmental can holders 3, when the carrier 2 is at a state of rest, Fig. 1 of the drawings.

From the guide ring 9 upwardly extend the guide rods 10, which in connection with the ring 9 form a holder for the can heads or covers 11, which are stacked therein flat one upon another, Fig. 5 of the drawings, and which are lowered successively through the guide ring 9.

Supported by the bracket 6 is a segmental support 12, onto which the flanged can bodies or cans 13 are delivered, and over which they are propelled by the segmental holders 3 of the rotary carrier 2 toward the can head or cover feed mechanism, the said support 12 being provided with an upward extension 14 which serves as a guide wall for holding the flanged can bodies or cans within the segmental holders as conveyed toward and from the can head feeder.

As stated, the feed blade 8 works through the guide plate 7, and preferably the same is thrown inwardly by a lever 15 fulcrumed to the bracket 6, constituting a portion of the frame 1, the said lever at its upper end being forced inwardly by the pressure of a heavy compression spring 17 interposed between the bracket 6 and the lower end portion of the fulcrumed lever 15, the pressure

of which holds the lower end of the said lever normally outward. The said lever is actuated to throw outwardly its upper end by a plurality of inclined cams 16 inwardly 5 projected from the rim of the gear 5, the said cams during the rotation of the gear 5 being successively engaged by an anti-friction roller 16', on the connecting link 17 working through a guide 17'. The slide 10 blade 8, when released, as hereinafter explained, is preferably thrown outwardly by a spring 18, acting against a pivoted lever arm 18', the upper end of which is in engagement with the outer end portion of the 15 slide blade 8, Fig. 1 of the drawings, and serves to return the same outwardly after having been forced inwardly by the action of the lever 15. The said lever 15 at its upper end bears loosely against the outer 20 end of the slide blade, when the same is in its outward position, Fig. 1 of the drawings. The rotary movement of the gear 5 is so timed that the roller 16' will be in engagement with one of the cams 16 to draw the 25 lower end of the fulcrumed lever 15 inwardly and hold outwardly the upper end thereof on the slide blade 8 being released for outward movement. As the roller 16' moves off of the inclined cam 16, the pressure 30 of the spring 17', which is secured at one end to the lever 15 and at its opposite end to the bracket 6, exerts itself to force outwardly the lower end of said lever 15 to throw inwardly the upper end thereof, the 35 pressure of which spring is sufficient to overcome the resistance of the spring 18 to throw the slide 8 in opposition thereto. The feed slide blade 8 when moved inward by the throw of the lever 15 is held locked in 40 said position by means of the locking catch 19, working through the guide plate 7 and normally held inwardly pressed by the action of the spring 19', and said catch engages with the notched section 20 of the 45 feed slide blade 8 at one side thereof adjacent its inner end, Figs. 2 and 4 of the drawings. The locking catch 19 is carried at the upper end of a rotatable stud 20', to the lower end of which is attached a projecting cam lever 21, which lever projects within the path of the flanged cans or can bodies 13 as conveyed by the carrier 2 toward the can head or cover feed mechanism. As the cam lever 21 is engaged by a propelled can or can body 13, the same is forced 50 outwardly, turning the stud 20 to release the lock catch 19 from engagement with the feed slide 8, which is withdrawn from beneath the guide ring 9 by the action of the 55 spring pressed arm 18', allowing the entire stack of retained can heads or covers 11 to lower the thickness or depth of one can head or cover. By this time the end flanged can or can body to receive a head or cover will 60 rest directly beneath the guide ring and the 65

released stack of covers or heads will stand directly above the opened flanged end thereof. Just prior to the action of the rotary carrier removing the can or can body from beneath the guide ring 9, the action of the lever 15 will have forced inwardly the feed slide 8, to place the inner end thereof between the lowermost two of the stack of can heads, the said feed slide or blade 8 when so positioned supporting the entire 70 stack of heads with the exception of the lowermost one which is cut out or separated from the remainder of the stack, the same being held free within the guide ring, resting either loosely on the flanged end of the can body or can, or, as hereinafter explained, loosely within the external segmental holder of the rotary carrier 2. The moment the feed slide 8 is moved inwardly the lock-catch 19 moves into engagement 75 with the notched section 20 of the said slide and holds the same in such position as a support for the stack of heads or covers until the cam lever is acted on by another can or can body. 80

In the present case, each segmental can holder 3 is formed with a segmental groove 3' into which the cut out can head or cover 11 is deposited a slight distance above the open flanged end of the can body or can, 85 being retained therein by the supporting rib 3² inwardly projecting from the segmental wall 14. The can cover or head is thus supported above the flanged end of the can or can body a slight distance and is 90 carried in alinement with the can or can body by the rotary carrier until delivered to the mechanism for seaming the can head or cover to the flanged end of the can or can body. However, the can head or cover 100 may be loosely applied to the flanged end of the can or can body direct from the can head feeder, such depending on the type of the seaming mechanism employed and also as to whether the heads are to be applied 105 to a flanged end filled can or to a flanged end can body. 110

The cans or can bodies 13 are delivered onto the support 12 in a vertical position and in this position are conveyed by the 115 rotary carrier 2 toward the can head or cover feed mechanism, and it is the action of the propelled can bodies or cans which act successively to release the lock catch for the feed blade. The can heads or covers are 120 thus only released by the action of the end flanged cans or bodies, consequently the heads or covers are only supplied on a flanged end can or body being positioned to receive the same. In other words the 125 operation of the working parts is such that if a can is not conveyed or propelled toward the feed mechanism for the can heads or covers, a release of the lowermost one of the supported stack of the heads or covers does 130

not take place, inasmuch as a can or body must be propelled for action against the cam lever 21 in order to release the retained heads or covers. The first action of the 5 propelled can or body to receive a head or cover is to throw the cam lever to release the locking catch 19, when the spring pressed arm 18' forces outwardly the feed slide blade 8, permitting the entire stack of 10 covers or heads 11 to lower through the guide ring 9 a distance equal to the depth of one cover or head, when the action of the fulcrumed lever 15 forces inwardly the said feed slide blade to cut out the lowermost 15 one of the stack of covers or heads and to uphold the remainder, the feed slide blade when so moved inwardly being held locked in such position by the locking catch 19 until released by the action of another can 20 or can body throwing the cam lever 21.

The working of the various parts of the machine is entirely automatic, and the working of the associate parts so timed as to come into action at the proper moment. 25 Preferably the rotary carrier 2 is driven with an intermittent movement, but this is an immaterial feature.

Referring to Figs. 2 and 3 of the drawings, it will be noted that the surface of the 30 rotary carrier 2 is cut away at a gradual downward inclination from the point *a* adjacent the forward upper edge of each of the external segmental can holders 3, onto which inclined surfaces the released can head or 35 cover seats itself and is gradually lowered onto the flanged end of the can or can body to which it is to be applied, or in the present case, onto the segmental rib 3² and within the segmental groove 3' of the can or can 40 body holders 3 for support immediately above and in alignment with the flanged opened end of the held can or can body. The mentioned inclined seat may be said to constitute a curved outward inclined extension 45 of the external segmental can or body holders, the purpose thereof being to prevent a sudden dropping of the released can head or cover.

The under surface of the feed slide blade 50 8 is in substantial alignment with the upper surface of the rotary carrier 2 which partly covers the bottom of the guide ring 9, Figs. 1 and 2 of the drawings, hence when the can stacked heads or covers are released they are 55 temporarily sustained by said rotary carrier and the rib 3² until the feed slide blade 8 is forced inwardly to cut out the lowermost one of the stack of heads or covers.

Having thus described the invention what 60 is claimed as new and desired to protect by Letters Patent is—

1. In a machine for the described purpose, the combination with a carrier provided with a plurality of holders for receiving and 65 holding can bodies to have heads applied

thereto, of a can head holder, a can head feeder for successively delivering can heads into alignment with the open end of cans carried by the carrier, a lock catch for normally holding the feeder locked against movement, means acted on by the propelled cans for releasing the lock catch of the can head feeder, and mechanism for actuating the can head feeder for releasing heads successively from the holder. 70

2. In a machine for the described purpose, the combination with a rotary carrier provided with a plurality of vertically disposed external segmental can holders, of a can head holder held above the rotary carrier, a reciprocating can head feed slide for sustaining can heads within the holder, a lock device for the feed slide, means acted on by cans propelled by the carrier for releasing the lock device as the cans are brought within the sphere of the can head holder, and mechanism for imparting reciprocating movements to the feed slide. 75

3. In a machine for the described purpose, the combination with a horizontal rotating carrier, a plurality of vertically disposed external segmental holders secured to the carrier for receiving and holding open ended cans in vertical position, a non-rotating support for said cans, of a can head holder arranged above the carrier and in alignment with the can holders carried thereby, a spring actuated reciprocating can head feed slide working beneath the can head holder and normally sustaining a stack 90 of can heads therein, lock means for holding the said feed slide locked beneath the can head holder, a device within the path of and acted on successively by the propelled cans for releasing the lock means to permit the 95 withdrawal of the feed slide from beneath the stack of retained heads, and mechanism acted on by the rotary carrier for forcing inwardly the feed slide to cut out the lowermost can head of the stack of said heads. 100

4. In a machine for the described purpose, the combination with a horizontally rotating carrier provided with a plurality of vertically disposed external segmental can holders, of a stationary segmental can support concentric with said carrier, a can head holder above the carrier, a reciprocating feed slide for sustaining a stack of can heads within the holder, devices for holding the slide in locked position beneath the stack of can heads, means thrown into action by a propelled can for releasing the feed slide, and mechanism for actuating the said feed slide to separate the lowermost head of the stack of can heads from the holder and depositing the same immediately above a can positioned by the carrier beneath the can head holder. 115

5. In a machine for the described purpose, the combination with a rotary carrier 120

provided with a plurality of external vertically disposed segmental can holders, and can head supporting seats, of a coöperating stationary can head supporting seat, a can head holder arranged above the carrier, a reciprocating can head feed slide operating with the holder to release and successively discharge can heads immediately above the open end of cans positioned by the carrier beneath the can head holder, a lock device for said feed slide, mechanism for imparting reciprocating movement of the feed slide, and means thrown into action by the propelled cans for releasing the locked feed slide.

6. In a machine for the described purpose, the combination with a carrier provided with a plurality of can holders for receiving and holding open end cans in vertical position, of a can head holder adapted to contain a stack of can heads located above the carrier, a slide plate for successively delivering can heads from the holder and positioning the same in alinement with the open end of a can positioned beneath the holder, a lock device for normally holding the slide plate locked with respect to the can head holder, and means acted on by the propelled cans for releasing the said lock device to free the said slide plate.

7. In a machine for the described purpose, the combination with a rotary carrier provided with a plurality of external vertically disposed segmental can holders, of an automatic can head feeder situated above the rotary carrier for alinement with the can holders thereof as moved beneath the same, devices for normally holding the can head feeder locked against movement, and means acted on by the propelled cans for actuating said devices to release the feeder for successively delivering can heads immediately above the cans as positioned beneath the same.

45 8. In a machine for the described purpose, the combination with a rotary carrier provided with a plurality of vertically disposed can holders, of a stationary can support, a segmental wall co-acting with the rotary carrier for the holding of flanged cans in the holders thereof, a can head holder, a reciprocating can head slide normally held locked beneath the can head holder for sustaining a stack of heads therein, devices acted on by the propelled cans for releasing the said slide, and means for actuating the released slide for successively discharging the can heads from the holder immediately above the open end of the cans as positioned beneath the said can head holder.

9. In a machine for the described purpose, the combination with a rotary carrier provided with a plurality of external segmental can holders, of a stationary segmental wall for holding end flanged cans within

70 said holders, a reciprocating can head feeder, locking means for normally holding the can head feeder locked against movement, a can head holder adapted to contain heads sustained by the can head feeder, mechanism for imparting reciprocating movement to the feeder, and means thrown into action by the movement of the propelled cans for releasing the locking means for the can head feeder.

75 10. In a can head feed mechanism, the combination of a rotary carrier provided with a plurality of can holders for cans to receive heads, a can head holder provided with a guide ring through which heads are 80 discharged, a reciprocating feed slide blade working beneath said ring for sustaining heads therein, a lock device for normally holding the feed slide against movement, mechanism for imparting reciprocating 85 movement to the feed slide blade when released, and means within the path of and acted on by the cans propelled by the rotary carrier for actuating the lock device of the feed slide blade to release the same for 90 successively feeding can heads to and immediately above the propelled cans.

95 11. In a machine for the described purpose, the combination with a rotary carrier provided with a plurality of vertically disposed can holders, of means co-acting therewith for securing open top cans in vertical position within said holders, a spring held can head feeder for successively supplying can heads to the held cans one at a time, 100 locking means for the can head feeder, a device acted on by the cans propelled by the carrier for releasing the locking means for the can head feeder for the release of can heads and delivery thereof to the propelled 105 cans immediately above the open end thereof, and mechanism for restoring the can head feeder to locked position.

110 12. In a machine for the described purpose, the combination with a rotary carrier provided with a plurality of can holders, of a can head holder, a reciprocating can head feed slide co-acting therewith, a spring held arm acting against the slide for outward movement, a fulcrumed lever for throwing 115 the slide inwardly, a lock device for holding the slide normally inward and beneath the can head holder, and means acted on by the cans propelled by the carrier to release the feed slide for successively feeding can heads 120 to the propelled cans.

125 13. In a machine for the described purpose, the combination with a carrier for the cans to receive heads, of a can head holder, a reciprocating head feed slide blade, a 125 spring held lock catch for normally holding the slide beneath the holder, means actuated during the movement of the carrier operating the slide to cut out the lowermost can head of the stack of heads within the holder, 130

a cam lever within the path of the propelled cans and actuated thereby to disengage the lock catch to release the feed slide blade, and spring held means for throwing outwardly 5 the released feed slide blade.

14. In a machine for the described purpose, the combination with a carrier for the cans to receive heads, of a reciprocating feed slide blade, a can head holder controlled 10 thereby, locking means for normally holding the feed slide beneath the can head holder, a device thrown into action by the propelled cans for releasing the feed slide, and devices for actuating the feed slide for successively 15 feeding can head covers to and immediately above the open end of the propelled cans.

15. In a machine for the described purpose, the combination with a can carrier provided with a plurality of can holders, 20 means for securing the cans within the holders during the movement of the carrier, of a vertically disposed holder above the carrier and in alinement with the can holders as carried beneath the same, said holder adapt-

ed to contain a stack of can head covers, a 25 head feed slide working beneath the can head holder and normally sustaining the stack of covers therein, locking means for holding the said slide normally inward and beneath the can head holder, and devices automatically and successively thrown into operation for releasing the said locking means to free the feed slide and move the same outwardly to uncover the can head holder for the lowering of the stack of covers therein 30 to place the lowermost one thereof within a can holder positioned beneath the can head holder, and to move the said slide inwardly to separate the lowermost cover from the stack of covers and close the can head 35 holder.

In testimony whereof I have signed my name to this specification in the presence of two subscribing witnesses.

AXEL JOHNSON.
